FASTENER INSERTING MACHINE

Clyde L. Knott, Beverly, Mass., assignor to United Shoe Machinery Corporation, Flemington, N. J., a corporation of New Jersey

Application April 13, 1949, Serial No. 87,218

14 Claims. (Cl. 1—18.1)

1

This invention relates to fastening inserting machines, and is illustrated herein as embodied in a fastening inserting machine of the type disclosed in United States Letters Patent No. 2,420,290, issued May 13, 1947, on an application filed in the name of A. D. Willhauck. The fastening inserting machine disclosed in the Willhauck patent is a heel seat lasting machine the general construction and operation of which is disclosed in United States Letters Patent No. 2,059,241, issued November 3, 1936, on an application filed in the name of J. C. Jorgensen.

It is a purpose of this invention to provide an improved fastening inserting machine of the type referred to, particularly to provide a machine more simplified and dependable in construction and operation as well as more readily adapted to operation upon different work thicknesses requiring fastenings of different lengths.

The illustrated machine, the same as the machine disclosed in the above-mentioned Willhauck patent, is provided with a set of tools which act alternately as awls and drivers, the tools when acting as awls being operated to make a series of holes in the work and thereafter when acting as drivers to insert fastenings into these holes. Thus the tools are operated twice in one cycle.

It is a feature of this invention to control the lengths of successive strokes imparted to the tools in accordance with the work thickness. More specifically, there is provided a movable stop, the position of which, with relation to an abutment carried by the tool operating mechanism, is adjustably determined in accordance with the work thickness, means being provided for so moving the stop that the first stroke of the tools when they act as awls is longer than the second stroke of the tools when they act as drivers. More specifically, the different lengths of the two strokes imparted to the tools in one cycle of operation are so determined that when the tools act as awls they penetrate the entire thickness of the work to provide holes therein, and when the tools act as drivers their operative stroke is shortened a distance corresponding to the work thickness or the lengths of the fastenings to be inserted into the previously made holes.

In accordance with another feature of the invention the movable stop is operated and controlled by means connecting this stop with the wiper operating mechanism with which machines of the above-identified type are provided. In particular, the arrangement is such that the

2

movement of the stop to determine the lengths of the strokes imparted to the tools in one cycle of operation is controlled by the wiper closing mechanism, that is, the mechanism which causes the two wipers to swing about a common axis toward each other to wipe the marginal portion of the shoe upper over the shoe bottom and into abutting relation with the shoe bottom member, usually the insole.

These and other features of the invention will now be described in detail in connection with the accompanying drawings and will be pointed out in the appended claims.

In the drawings,

Fig. 1 is a front elevation, partly in section, of the upper portion of a heel seat lasting machine embodying features of the present invention;

Fig. 2 is a right-hand side elevation of various mechanisms for actuating and controlling the operating instrumentalities of the machine, a lower portion of the machine being shown as broken away and oriented in elevation with respect to the rest of the machine;

Fig. 3 is a section along the line III—III of Fig. 1;

Fig. 4 is a section along the line IV—IV of Fig. 1;

Fig. 5 is a section along the line V—V of Fig. 1;

Fig. 6 is a section along the line VI—VI of Fig. 1;

Fig. 7 is a section along the line VII—VII of Fig. 1; and

Fig. 8 is a section along the line VIII—VIII of Fig. 1.

Since the purpose as well as the general construction and operation of the heel seat lasting machine herein shown is, in substance, the same as that described in the above-identified Letters Patent, only such portions of the illustrated machine as it is necessary to refer to for a complete understanding of the present invention will be herein described in detail. Machines of the illustrated type are designed especially for shaping a shoe upper about the heel end of a last and accordingly these machines include wipers for wiping the marginal portion of the upper inwardly over a sole member on the last bottom and, furthermore, such machines include means

for driving a plurality of fastenings to secure the overwiped marginal portion of the upper in lasted relation to the sole member. For supporting the shoe and last, there is provided a jack (not shown), the jack being mounted for forward and rearward swinging movement to pre-

sent the shoe to the operating instrumentalities of the machine or to move the shoe out of the machine after the completion of the heel seat lasting operation thereon. The jack is preferably controlled by a treadle (not shown) by which the operator may raise it after swinging it rearwardly to carry the shoe into engagement with a heel band (not shown) and to bring the heel seat face of the shoe into contact with shoe positioning means (not shown).

For wiping the marginal portion of the upper inwardly over the sole member about the heel end of the last the illustrated machine is provided with two wipers 10 (Figs. 1 and 8) which are arranged for rectilinear forward and rearward movement in the machine as well as for inward or outward swinging movement toward or away from each other about a common axis x (Fig. 8). In the power operation of the machine, the wipers 10 are advanced lengthwise of the supported shoe and are also swung toward each other or closed in automatically determined time relation by mechanism to be described. Each wiper 10 is secured to the bottom face of a wiper carrier 12 at the inner edge thereof. Rectilinear forward and rearward motions as well as swinging motions about the axis x are imparted to the two wiper carriers 12 for operating the wipers 10 accordingly. To control these swinging motions, there are provided circular guideways 14 in a slide 16 which is movable forwardly and rearwardly in the machine in a rectilinear path, the guideways 14 being engaged by guide tongues 18 provided on the lower faces of the wiper carriers 12 at the outer edges thereof. The guideways 14 and guide tongues 18 are curved about the axis x as a center and, accordingly, each wiper carrier 12 with the corresponding wiper 10 supported thereon may be swung about the axis x by movement with relation to the slide 16. Each wiper carrier 12 may also be moved forwardly or rearwardly in the machine in a rectilinear path by movement of the supporting slide 16 in these directions.

For controlling the movements of the slide 16 forwardly or rearwardly in the machine there are provided guideways 20 in the machine frame 22, in which guideways the slide 16 is received. As has been pointed out, in the wiping operation the wipers 10 are advanced in a rectilinear path forwardly of the machine and are closed or moved toward each other in time relation to that advancing movement. This is effected by advancing the slide 16 in its guideways 20 and imparting swinging movements to the wiper carriers 12 toward each other and with relation to the slide 16. There is a single advancing and closing movement of the wipers in one cycle of operation.

For advancing or retracting the slide 16 a rearward extension 24 thereof (Fig. 8) carries a cam roll 26 which engages a cam track 28 (Fig. 2) provided in the front end of a cam barrel 30. The cam barrel 30 is secured on a power-driven shaft 32 rotatably mounted in the machine frame 22.

For swinging the wiper carriers 12 and corresponding wipers 10 about the axis x each wiper carrier 12 has pivotally connected thereto a link 34 (Fig. 8) extending rearwardly therefrom and pivotally connected at its rear end to a rack bar 36 which is slidable in the machine frame in directions forwardly and rearwardly of the machine. In meshing engagement with the two rack bars 36 are gear segments 38 mounted to swing about fixed pivot studs 40 and integral

with opposite gear segments 42 that mesh with teeth provided on the opposite sides of a rack slide 44 mounted in the machine frame for movement forwardly and rearwardly of the machine. The rack slide 44 carries on it a cam roll 46 which engages a cam track 48 (Fig. 2) provided in the rear portion of the previously mentioned cam barrel 30.

The above-mentioned mechanism for inserting 10 fastenings, in the illustrated example, is adapted to insert into the work fiber pegs which are severed from strands of fiber fastening material that are intermittently fed into the peg forming and inserting mechanism. No fiber strand feeding mechanism is illustrated herein since it is not a part of the present invention, but for a full disclosure of such a mechanism reference may be had to an application for Letters Patent of the United States Serial No. 738,095, filed 20 March 29, 1947, in my name, upon which Patent No. 2,510,234 was granted on June 6, 1950. As fully disclosed in the aforementioned Willhauck patent the fiber pegs are intermittently severed in a gang from a series of strands of fiber fastening material and are then presented in driving position by being delivered to vertical guide passages provided in upstanding flanges 50 (Figs. 1 and 8) at the inner or wiping edges of the wipers 10. These wiping edges of the wipers, 25 in the closed position of the wipers, make a U-shaped outline, as seen in the plan, in conformity to the heel seat portion of the shoe which is being operated upon. The pegs, after 30 they have been transferred to the just-mentioned passages in the flanges 50 of the wipers are inserted into the heel seat portion of the shoe by a gang of vertically movable tools 52 (Fig. 1). The tools are arranged in two groups of arcuate 35 rows, one group being provided for each wiper 40 10 and associated parts. The tools 52 have a dual function in that they act alternately as awls to make holes in the heel seat portion of the shoe and as drivers to insert the previously severed and transferred fiber pegs into these holes. Accordingly, two power strokes are given to the tools 52 in each cycle of operations.

In the following, only the parts of the fastening forming and driving mechanism associated 50 with one of the two wipers 10 will be described in detail, it being understood that another assembly of corresponding elements is associated with the other wiper and arranged in symmetrical relation to the assembly of elements now to be described.

Secured to the wiper carrier 12 and located 55 above and in spaced relation to the flange 50 of the wiper 10 is a tool guiding block 54 (Figs. 1 and 6) having vertical passages arranged in an arcuate row for guiding the vertically moving tools 52 as well as having spaced from these 60 passages an arcuate row of bores which serve to guide the strands of fastening material in their downward travel into fastening severing position. Also secured to the wiper carrier 12 and arranged 65 in contiguous relation to the tool guiding block 54 is an upstanding bracket 56 (Figs. 1 and 5). To the upper portion of the bracket is secured a block 58, the block having a curved slot 60 (Fig. 4) through which freely extend flexible 70 tubes 62 which guide the fiber strands downwardly. Provided in the block 58 is, furthermore, a vertical bore in which is received a vertically reciprocating tool operating bar 64 which is prevented from rotation about its longitudinal axis 75 by a spline (not shown). The inner ends of the

two blocks 58 overlap each other and are vertically bored to receive a fulcrum pin 66, the vertical axis of which coincides with the previously mentioned axis x. Removably secured to the lower end of each bar 64 is an arc-shaped row of tools 52, the lower ends of which extend into the corresponding tool guiding block 54 even when the bars assume their uppermost positions.

Since the tools 52 and the two tool operating bars 64 are supported in the two brackets 56 and since the brackets 56 are secured to the wiper carriers 12 and thus participate in the forward and rearward as well as opening and closing movements of the wiper carriers 12, a sliding connection is provided between the upper ends of the bars 64 and the means for reciprocating the bars vertically. More specifically, the bars 64 are provided near their upper extremities with annular horizontal grooves forming rounded heads on the bars. The bars are actuated by means of power operated links 68 (Fig. 1) which are connected to the bars as follows: Pivotally secured to the lower extremity of each of the two links 68 is a block 70 provided with a horizontal T-shaped slot in which the rounded head of the bar 64 is received. Retaining plates 72 secured to the links 68 serve to hold the blocks 70 in position. Thus the bars 64 may participate in the movements of the wiper carriers 12 without disturbing their driving connections with the links 68.

The inner and lower portions of the brackets 56 are provided with vertical bores arranged in arcuate rows for the passage therethrough of the strands of fiber fastening material. These bores are vertically aligned with the above-mentioned strand guiding bores provided in the tool guiding blocks 54. Secured to each bracket 56, at the upper ends of the strand guiding bores, is a perforated strand tube plate 74 (Figs. 1 and 5) which receives the lower ends of the strand guiding tubes 62. Provided on the lower end of each tool operating bar 64 is a foot block 76 (Fig. 5) and each foot block has in its lower face an arcuate guideway in which the heads of the tools 52 are removably secured.

For receiving the lower ends of the fiber fastening strands during each feed movement thereof, and for severing fiber pegs from these strands, there are provided two shear blocks 78 (Figs. 1, 6 and 7) which are mounted for horizontal movement in guideways 80 provided between the tool guiding blocks 54 and the wiper carriers 12. The shear blocks 78 are positively reciprocated between two fixed positions and are provided with an arcuate row of vertical bores. In the retracted position of each shear block 78, as illustrated in Fig. 1, the vertical bores therein are in alignment with the above-mentioned strand guiding bores in the tool guiding block 54 so that on downward movement of the fiber strands the lower ends of the strands are inserted to a predetermined extent into the vertical bores of the shear blocks 78. After the insertion of the strands into the blocks 78 the blocks are advanced inwardly or toward each other to sever the lower portions of the fiber strands therefrom to form pegs. The advancing movement of each shear block 78 is terminated by stops (not shown) when the vertical bores therein containing the fiber pegs are in alignment with the vertical guide passages in the flanges 50 of the wipers 10 as well as with the vertical tool guiding passages in the corresponding tool guiding blocks 54. The pegs are now located in the line of drive of the

tools 52 which are in their retracted upper position above the pegs.

For the purpose of reciprocating each shear block positively, power operated mechanism is provided. A bell crank lever 82 (Figs. 1, 6 and 7) has a downwardly extending arm carrying a pin 84 on which are mounted, at opposite sides of that arm of the bell crank lever 82, fulcrum blocks 86. These blocks 86 engage a transverse groove 88 provided in the top face of the shear block 78 and also are located between spaced upstanding lugs provided on the shear block at opposite sides of the groove 88. The bell crank lever 82 is pivotally secured by a pin 90 (Fig. 6) to a lug secured to the bracket 56. Two parallel upwardly extending arms of the bell crank lever 82 carry a pin 92 on which is rotatably mounted a pivot block 94 arranged between the arms of the bell crank lever 82 and located in a C-shaped piece 96 (Fig. 1) integral with the lower end of a vertically reciprocating plunger 98. The plunger is guided in a sleeve which is part of the bracket 56 and, accordingly, the plunger participates in the above-referred-to movements of the wiper carrier 12. Thus, it is necessary to provide also a sliding connection between the upper end of the plunger 98 and the means for vertically reciprocating the plunger. There is provided an annular horizontal slot near the upper end of each plunger 98 forming a rounded head on the upper end of the plunger, which head is received in a horizontal T-shaped guideway or slot 100 (Fig. 3) provided in the underface of an arm 102. The arm 102 is pivotally secured by a pivot stud 104 to a foot plate 106 which in turn is rigidly secured to the lower end of a vertically reciprocated rod 108. The outer end of the foot plate 106 is shaped to form a guiding ridge 110 along which an upstanding and overhanging flange 112 (Fig. 2) provided on the arm 102 may move. Thus, in spite of the participation of each plunger 98 in the wiper movements, driving connection of each plunger with its respective actuating rod 108 is maintained, it being understood that the rods 108 are arranged in the machine for vertical reciprocation only.

For the purpose of reciprocating the rods 108 in the machine frame, their upper ends are pivotally secured to the forked front end of a two-armed lever 114 (Fig. 2) which is pivotally secured to the machine frame at 116. The rear end of the lever 114 is pivotally connected by a link 118 to a slide 120 which is mounted for vertical reciprocation in the machine frame. The lower end of the slide 120 carries a cam roll 122 which is engaged in a cam groove provided in one face of a cam disk 124 on the shaft 32, the cam disk also functioning as a power transmitting gear. Thus the lever 114 is rocked by the cam 124 in time relation to the operation of the operating instrumentalities of the machine to advance and retract the shear blocks 78 with the results described.

In order to actuate the tools 52 twice in one cycle of operations, first with a long stroke, then with a shortened stroke, as previously explained, the above-described links 68 are pivotally secured to the front end of a lever 126 (Fig. 2) which passes through a vertically elongated aperture in a plunger 128 mounted for vertical reciprocation in the machine frame. A pin 130 pivotally secures the lever 126 to the plunger 128. The rear end of the lever 126 is provided with a horizontal slot 132 open at its rear end and engaging a flattened portion of a pivot shaft 134 rotatably

mounted in the machine frame. Accordingly, the lever 126 is swung about the axis of the shaft 134 on vertical reciprocation of the plunger 128. The slot 132 is provided for the purpose of permitting the lever 126 to move slightly with relation to the shaft 134 in view of the fact that the pivot pin 130 of the lever 126 is constrained to move in a vertical path only. The plunger 128 is elevated by a lift cam 136 secured to the front end of the shaft 32 and engaging a roll 138 rotatably mounted on the lower extremity of the plunger 128. Secured to the upper end of the plunger 128 is a casing 140 (Fig. 1) open at its top in which is housed a heavy spring 142 the lower end of which engages the bottom of the casing 140 and the upper end of which is in engagement with a bolt 144 adjustably secured in the machine frame. It will be seen, therefore, that on elevation of the plunger 128 by the lift cam 136 the spring 142 is loaded. The configuration of the lift cam 136 is indicated in dotted lines in Fig. 1 which shows two drops or lower portions. Thus on rotation of the cam through one complete revolution, corresponding to one cycle of operations, the plunger 128 is twice raised by the cam and is twice permitted to drop under the force of the loaded spring 142. Accordingly, the tool operating plunger 128 is actuated twice in one cycle of operations to impart two operating movements to the tools 52.

As has been stated, the two operating movements imparted to the tools 52 in one cycle of operations are of different lengths. The lengths of the successive tool strokes are controlled by the following mechanism: A movable stop in the form of a sliding wedge 146 (Fig. 2) is mounted for forward and rearward movement in a guide piece 148 secured in the machine frame. The wedge 146 and the guide piece 148 are provided with central clearance holes through which the plunger 128 extends, the hole in the wedge 146 being elongated in the lengthwise direction of the wedge to enable the wedge to be moved forwardly and rearwardly in the machine with relation to the plunger 128. As illustrated in Fig. 2, the upper face of the wedge is horizontal and only its lower face is inclined with relation to the path of movement of the tool operating plunger 128, this inclined face of the wedge being guided by a similarly inclined face provided in the guide piece 148. Secured on the wedge 146 is an annular pad 150, or cushion, which, on downward movement of the plunger 128, is engaged by a circular abutment 151 provided on the plunger 128 and normally located above the pad 150. Engagement of the abutment 151 with the pad 150 terminates the downward movement of the plunger 128 and, accordingly, determines the length of operating movement imparted to the tools 52. Displacement of the wedge toward the left or the right of Fig. 2 varies the heightwise position of the pad 150 and accordingly varies the extent of downward movement of the plunger 128 and thus of the stroke of the tools 52. It will be understood that when the tools 52 act as awls, the wedge is in a right-hand position and the pad 150 is lowered to lengthen the first stroke of the tools 52. When, thereafter, that is, after the re-elevation of the plunger 128 by the lift cam 136, the tools 52 are to act as drivers, the wedge is displaced to its leftmost position in Fig. 2 so as to raise the pad 150 a predetermined amount and consequently shorten the next downward movement of the plunger 128 a predetermined amount, this amount corre-

sponding to the work thickness and the length of the peg to be inserted.

The arrangement is such that regardless of the thickness of the work the wedge 146 always occupies the same leftmost position in Fig. 2 prior to the operation of the tools 52 as drivers. In this leftmost position of the wedge the tools 52 are stopped with their lower ends in the plane of the under-faces of the wipers, the wipers then firmly engaging the upper face of the work. Thus the tools 52 drive the pegs home with the trailing ends of the latter flush with the upper surface of the work. Only the first stroke of the tools 52 when they act as awls is varied in accordance with the work thickness to secure a complete penetration of the work by the tools. Of course the lengths of the pegs is also predetermined in accordance with the work thickness.

To determine the positions of the wedge 146 between successive downward movements of the plunger 128, the following mechanism is provided. The right-hand end of the wedge 146 (as viewed in Fig. 2) is pivotally connected by a link 152 to the free end of an arm 154 secured on and depending from a shaft 156 rotatably mounted in the machine frame. Secured on the shaft is also an upwardly extending arm 158 to the free end of which is pivotally secured the upper end of a link 160. The lower end of the link is adjustable along a curved guideway 162 provided in the upwardly extending curved arm 164 of a bell crank lever which is pivotally secured at 166 to the machine frame. The lower end of the link 160 is held in adjusted position in the guideway 162 by a conventional binding bolt 170 having a T-shaped head at its inner end which is drawn into binding engagement with the T-shaped guideway 162 by a hand wheel 168 on the bolt. The lower arm 172 of the bell crank lever carries a cam roll 174 which is engaged in the previously mentioned cam groove 48 in the cam barrel 30. As will be remembered the cam groove 48 serves to impart swinging movement, that is, opening and closing movements, to the wipers about the axis x and as has been determined the configuration of the cam groove 48 is such that in the selected position of the cam roll 174 in the cam groove 48 as shown in Fig. 2 it can serve also to operate the wedge 146 in time relation to the operation of the operating instrumentalities of the machine, particularly the tools 52 and the tool operating mechanism. Adjustment of the lower end of the link 160 with relation to the pivot 166 of the bell crank lever 164, 172 along the guideway 162 adjusts the effective length of the arm 164 of the bell crank and, accordingly, varies the extent of movement of the wedge 146 from its fixed leftmost position toward the right of Fig. 2. The arm 164 therefore is preferably provided with a scale (not shown) on which different work thicknesses are marked so that the operator may adjust the lower end of the link 160 opposite the marking on the arm 164 corresponding to the thickness of the work operated upon. The cam track 48 is of such configuration that prior to the first operation of the tools 52 it displaces the wedge to the right of Fig. 2 a predetermined amount, depending on the setting of the link 160, thus insuring a predetermined long stroke of the plunger 128 and accordingly of the tools 52, and that prior to the second actuation of the tools 52 it displaces the wedge 146 into its leftmost position in Fig. 2 to raise the pad into its fixed uppermost position, 75 regardless of the setting of the link 160, thus to

shorten the second downward movement of the plunger 128 and, accordingly, always to terminate the second stroke of the tools 52 when their lower ends are in the plane of the under-faces of the wipers.

The reason why the wedge 146 always moves to the same left-hand end position in Fig. 2 irrespective of the setting of the link 160 may be explained as follows: After the actuation of the tools 52 as drivers the cam track 48, due to its configuration, swings the bell-crank lever comprising the arms 164 and 172 (in a clockwise direction—Fig. 2) into a position in which the center of curvature of the guideway 162 coincides with the axis of the pivotal connection between the arm 158 and the link 160. Thus no matter what position the lower end of the link 160 occupies along the curved guideway 162 the pivotal connection between the arm 158 and the link 160 is always moved to the same position and, accordingly, the wedge 146 is always moved into the same left-hand end position. But on reverse swinging movement of the bell-crank lever 164, 172 (in a counterclockwise direction—Fig. 2) the setting of the link 160 variably determines the extent of movement of the wedge 146 toward the right of Fig. 2, the setting of the link 160 being so selected that the extent of the movement of the wedge toward the right of Fig. 2 is proportionate to the thickness of the work.

The operation of the machine will now be described. After the shoe, the heel seat portion of which is to be lasted and pegged, has been properly located in the machine and the machine cycle has been initiated the wipers 10 are first caused to be advanced and to be closed to wipe the marginal portion of the shoe upper over the sole member. While the wipers remain in their advanced and closed operative positions the tools 52 are given their long stroke in that the first drop of the cam 136 permits the loaded spring 142 to depress the plunger 128 to its lowermost position as determined by the wedge 146. In this case the tools 52 act as awls passing through the vertical guide passages provided in the flanges 50 of the wipers 10 into and through the overwiped marginal portion of the upper as well as through the heel seat portion of the sole member against which the overwiped marginal portion of the upper is held pressed by the wipers 10. The length of this stroke of the tools 52 is so controlled by the adjustable wedge 146 that the tools 52 terminate their punching movement after having completely penetrated the combined thickness of the work parts. Thus an arc-shaped row of holes is provided in the heel seat portion of the shoe and the tools 52 thereafter are withdrawn as a result of the lifting of the plunger 128 by the cam 136. The wipers 10 remain in their closed operative positions. In the meantime, the strands of fastening material have been fed into the shear blocks 78 and, as a result of the operation of the lever 114 by the cam 124, the shear blocks are then advanced to sever a series of pegs from the strands and to present the pegs in the line of drive of the elevated tools 52. After the re-elevation of the plunger 128 and the tools 52 the wedge 146 is moved to its left-hand end position in Fig. 2 by its actuating mechanism which derives its movement from the wiper closing cam track 48 as described. The movement of the wedge 146 toward the left of Fig. 2 elevates the pad 150 a distance corresponding to the work thickness and to the length of the pegs to be inserted. The second downward movement of the

plunger 128 by the loaded spring 142 is then permitted by the second drop of the cam 138 but this second downward movement of the plunger 128 is of shorter extent in view of the previous shifting of the wedge 146 and elevation of the pad 150. Accordingly, the tools 52 which now act as drivers are caused to stop with their lower ends in the plane of the under-faces of the wipers and thus in positions which are spaced from the previously reached lowermost positions a distance corresponding to the length of each peg. The tools 52 when acting as drivers move through the vertical bores of the shear blocks 78 which bores are then aligned with the vertical path of movement of the tools, the tools engaging the pegs contained in the bores of the shear blocks 78 and driving them through the passages in the wiper flanges 50 and inserting them into the work. Since the tools 52 when acting as drivers stop with their lower ends located substantially at the level of the upper surface of the work the pegs are driven flush into the work. The lower ends of the pegs may become upset in meeting the usual metal heel plate on the heel seat portion of the last bottom. The pegs having been inserted into the holes previously made in the work, and thereby securing the upper in lasted relation to the shoe bottom, the tools 52 are re-elevated as a result of the renewed elevation of the plunger 128 by the cam 136. The shear blocks 78 are then retracted by their respective actuating mechanisms and also the wipers are opened and withdrawn by the wiper operating mechanism. The machine parts having been returned to their initial position the shoe is released and removed from the machine and the machine is ready for the operation upon the next shoe to be presented to it.

Having thus described the invention, what I claim as new and desire to secure by Letters Patent of the United States is:

1. In a fastening inserting machine, a tool acting alternately as an awl and a driver, tool-operating mechanism, an abutment included in the tool operating mechanism, a movable stop engageably cooperating with the abutment to terminate each operating movement of the tool, means for moving the stop with relation to the abutment prior to each operation of the tool and means for so adjusting the stop moving means that the extent of movement imparted to the stop may be varied in accordance with the thickness of the work operated upon.
2. In a fastening inserting machine, a tool acting alternately as an awl and a driver, tool-operating mechanism, an abutment included in the tool-operating mechanism, a stop movable between two end positions in each of which it is located in a predetermined operative relation to the abutment to terminate successive strokes of the tool at different levels, means for moving the stop prior to each operation of the tool, and means for adjusting the throw of the stop-moving means in accordance with the thickness of the work operated upon so as to cause the two end positions of the stop to be spaced apart a distance corresponding to the thickness of the work.
3. In a fastening inserting machine, a tool acting alternately as an awl and a driver, tool-operating mechanism, an abutment included in the tool-operating mechanism, a movable stop cooperating with the abutment to terminate the operating movements of the tool, and means for locating the stop in a fixed end position prior to the operation of the tool as a driver and for

moving the stop, prior to the operation of the tool as an awl, out of that end position a predetermined distance adjustable in accordance with the work thickness.

4. In a fastening inserting machine, a tool having two strokes in one cycle of operations and acting alternately as an awl and a driver, tool-operating mechanism, an abutment included in the operating mechanism, a stop engageably cooperating with the abutment to terminate each operative movement of the tool, means for positioning the stop to engage the abutment and terminate the first stroke of the tool when the tool has fully penetrated the entire thickness of the work, and means active before the second stroke of the tool to reposition the stop so as to engage the abutment and terminate the second stroke of the tool when the leading end of the tool is at the top surface of the work.

5. In a fastening inserting machine, a tool acting alternately as an awl and a driver, tool-operating mechanism, an abutment included in the operating mechanism, a movable stop cooperating with the abutment when the tool acts as an awl, movable link and lever mechanism connected to the stop, means for adjusting the throw of the link and lever mechanism in accordance with the thickness of the work operated upon, and power-operated means active immediately prior to the operation of the tool as an awl to operate the link and lever mechanism so as to move the stop into a predetermined operative relation to the abutment.

6. In a fastening inserting machine, a tool acting alternately as an awl and a driver, tool-operating mechanism, an abutment included in the operating mechanism, an adjustable wedge member acting as a stop for the abutment, and means adjustable in accordance with the thickness of the work for moving the wedge member away from the abutment, prior to the operation of the tool as an awl and for moving the wedge member toward the abutment prior to the operation of the tool as a driver.

7. In a fastening inserting machine, a tool acting alternately as an awl and a driver, a tool-operating member, an abutment carried by said member, a guide member having a guiding surface inclined with relation to the path of movement of said operating member and abutment, a wedge member engaging said surface and movable with relation to said guide member to act as a stop to terminate the operative movements of the tool at different levels, means for moving the wedge member, and means for adjusting the stroke of said moving means in accordance with the thickness of the work operated upon thereby causing the wedge member to be moved into a selected predetermined position with relation to the abutment prior to the operation of the tool as an awl.

8. In a fastening inserting machine, a tool, a tool-operating member having two strokes during one cycle of operations, the tool acting as an awl during the first stroke and as a driver during the second stroke, a movable stop engageable with said member to terminate each of said strokes, means active between successive strokes of said member to adjust the stop in different engaging positions with relation to the tool-operating member, thereby varying the lengths of the successive strokes of the tool, and means for initially adjusting the stop-adjusting means in accordance with the thickness of the work operated upon.

9. In a fastening inserting machine, a tool, a tool-operating member having two strokes of different lengths during one cycle of operations, the tool acting as an awl during the first stroke and as a driver during the second stroke, a stop for the tool-operating member movable to lengthen the first stroke of the tool-operating member, stop-operating mechanism for moving the stop with relation to the tool-operating member to cause the first stroke of the latter member to be lengthened, and means for adjusting the stroke of the stop-operating mechanism in accordance with the thickness of the work operated upon so as to cause the stop to increase the length of the first stroke of the tool-operating member a distance corresponding to the thickness of the work.

10. In a fastening inserting machine, a tool, a tool-operating member having two strokes of different lengths during one cycle of operations, the tool acting as an awl during the first stroke and as a driver during the second stroke, a stop for the tool-operating member movable to lengthen the first stroke of the tool-operating member, stop-operating mechanism for moving the stop with relation to the tool-operating member to cause the first stroke of the latter member to be lengthened, and means for variably adjusting the stroke of the stop-operating mechanism in accordance with variations in the thickness of the work so as to cause the stop to increase the length of the first stroke of the tool-operating member over the length of the second stroke a distance corresponding to the thickness of the work.

11. In a fastening inserting machine, a tool, a tool-operating member having two strokes during one cycle of operations, the tool acting as an awl during the first stroke and as a driver during the second stroke, an abutment secured to the tool-operating member, a movable stop engageably cooperating with the abutment during the first stroke of the tool-operating member variably to determine the length of said first stroke in accordance with the work thickness, and means for moving the stop with relation to the abutment immediately prior to the first stroke of the tool-operating member.

12. In a fastening inserting machine, a tool acting alternately as an awl and a driver, tool-operating mechanism, an abutment included in the tool-operating mechanism, a movable stop cooperating with the abutment to terminate the operating movements of the tool, and means for moving the stop with relation to the abutment prior to each operation of the tool, said means including means for adjusting the extent of movement imparted to the stop to correspond to the thickness of the work operated upon.

13. In a fastening inserting machine, a tool acting alternately as an awl and a driver, a tool-operating member having two strokes toward a work support during one cycle of operations, a movable stop engageably cooperating with a portion of the operating member on each of said strokes for variably limiting the movement of the tool toward the work support, stop-moving mechanism, retractable means for wiping the work into clamped relation with its support, mechanism for operating said means, and connections between said last-mentioned mechanism and the stop-moving mechanism for actuating the latter.

14. In a fastening inserting machine, a tool acting alternately as an awl and a driver, a tool-

13

operating member having two strokes toward a work support during one cycle of operations, a movable stop engageably cooperating with a portion of the operating member on each of said strokes for variably limiting the movement of the tool toward the work support, stop-moving mechanism, means adjustable in accordance with the thickness of the work operated on for adjusting the throw of the stop-moving mechanism, retractable means for wiping the work into clamped relation with its support, mechanism for operating said means, and connections between said last-mentioned mechanism and the stop-moving mechanism for actuating the latter.
